UNITED STATES PATENT OFFICE.

PAUL C. BURHANS, OF GLENDALE, MONTANA, ASSIGNOR OF ONE-HALF TO WALLACE E. DUNKERLEY, OF GLENDALE, MONTANA.

ROTARY STEAM-ENGINE.

No. 920,911.

Specification of Letters Patent.

Patented May 11, 1909.

Application filed August 21, 1908. Serial No. 449,695.

To all whom it may concern:

Be it known that I, PAUL C. BURHANS, a citizen of the United States, residing at Glendive, in the county of Dawson and State of Montana, have invented a new and useful 5 Rotary Steam-Engine, of which the following is a specification.

This invention relates to rotary engines and has for its principal object to provide a 10 novel form of engine in which the steam may be cut off at any desired point in the stroke and thereafter used expansively.

A further object of the invention is to provide an engine of this type in which the 15 entering volume of steam is discharged against the piston in such manner that both its pressure and impact may be used.

A still further object of the invention is to provide a novel form of reversing mech- 20 anism.

With these and other objects in view, as will more fully hereinafter appear, the invention consists in certain novel features of construction and arrangement of parts, more 25 fully hereinafter described, illustrated in the accompanying drawings, and more particularly pointed out in the appended claims, it being understood that various changes in the form, proportion, size and minor details 30 of construction may be made without departing from the spirit or sacrificing any of the advantages of the invention.

In the accompanying drawings:—Figure 1 is a side elevation of a rotary engine con- 35 structed in accordance with the invention, a portion of the cylinder being broken away in order to illustrate the interior construction. Fig. 2 is a view looking from the opposite side of the engine. Fig. 3 is an end 40 elevation. Fig. 4 is a vertical section of the engine on the line 4—4 of Fig. 3. Fig. 5 is a section on the line 5—5 of Fig. 4. Fig. 6 is a detail transverse section of the main 45 valve.

Similar numerals of reference are em- 50 ployed to indicate corresponding parts throughout the several figures of the drawings.

The main body 10 of the cylinder and the 55 base 11 are preferably formed of an integral casting, the cylinder being bored out for the reception of the piston and to the opposite sides of the main casting are secured the cylinder heads 12. The cylinder heads are provided with openings for the passage of

a shaft 13, and any suitable bearings may be provided for the shaft at points outside the heads. Secured rigidly to the shaft is a cylindrical piston drum 14, that is provided with a projecting wing 15, the opposite ends 60 and the outer edges of the wing being provided with grooves for the reception of packing strips 16 that may be formed of any suitable material.

To the top of the cylinder is secured a 65 casting 18 forming an abutment chamber and steam chest the former being arranged for the reception of a vertically movable abutment 19, which is provided with obliquely disposed grooves 20 for the reception 70 of packing strips 21. This abutment is carried by a vertically disposed rod 22 that extends out through a stuffing box at the top of the casing 18, and bearing on the top of the abutment is a compression spring 24 that 75 tends to hold the abutment yieldingly against the periphery of the piston drum for the purpose of preventing the escape of steam from side to side of the abutment.

Secured to the shaft 13 is a disk 25 hav- 80 ing a cam groove 26 that is arranged for the reception of a projection or anti-friction roller 27 that is disposed at the lower end of a vertically movable bracket 29 that projects from one of the cylinder heads. The 85 upper end of the rod is connected to the top of the rod 22 by means of a lever 30 that is centrally fulcrumed on a bracket 31, that is secured to the top of the casing 18.

At one end of the casing 18 is arranged a 90 steam chest 34 that preferably is cylindrical in form, and with this chest communicates a main steam pipe 35. Leading from the chest are two steam pipes 36 and 37 which communicate with valve chambers 38 and 95 39. In the main steam chest is a rocking valve 40 having a stem 41 that projects beyond the steam chest and carries an arm 42, said arm being connected by a pitman 43 to a sliding block 44 that is arranged in a link 100 45 pivoted at 46 to one of the cylinder heads. One end of the link 45 is connected by a rod 48 to the strap of eccentrics 49 on the main shaft 13, and as the shaft revolves the eccentrics will oscillate the link 45 and 10 thereby impart rocking movement to the valve 40. This will open and close the valve for the purpose of cutting off the entrance of steam at any desired point so that the first part of the stroke or revolu- 11

tion may be accomplished by the impact and pressure of steam, and the remaining portion of the stroke accomplished by the expansion of the body of steam admitted to 5 the working space of the cylinder.

At a point adjacent the engine is pivoted a combined cut off and reversing lever 50 that is provided with a latch bolt of ordinary construction arranged to engage a 10 notched locking quadrant 51. From this lever extends a rod 52 that is connected by a link 53 to the link block 44 so that the position of the link may be shifted for the purpose of altering the point of cut off of 15 the main valve 40.

The two valve casings 38 and 39 communicate with the working space of the cylinder through curved inlet ports 55 and 56 said ports being curved in such manner as to 20 direct the volume of entering steam against the piston wing 15 so that the impact of the steam may be utilized as well as its pressure. In the casings 38 and 39 are arranged reversing valves 57, the stems of which are 25 connected by arms 58 to the rod 52 and when the parts are in the position shown in Fig. 1, the port 56 is the inlet port, while port 55 is the exhaust port. Should it be 30 desired to reverse the direction of the piston, the lever 50 is pulled to the right and the block 44 is thus shifted beyond the pivot point 46 so that the position of all three valves is reversed and the port 55 will then 35 become the inlet port while port 56 becomes the exhaust port, and the valve 40 will then operate to direct the entering steam to the valve casing 38.

What is claimed is:

1. In a rotary engine, a cylinder, a shaft 40 extending therethrough, a piston in said

cylinder, a piston wing extending from the piston, a movable abutment arranged to press against the periphery of the piston, a cam carried by the shaft and arranged to actuate the abutment, a steam chest, a valve 45 therein, means for actuating said valve, a pair of reversing valves, ports controlled by said valves, the ports being arranged at opposite sides of the abutment and being curved to direct the entering steam against 50 the piston wing, and a combined cut off and reversing lever connected to all of said valves.

2. In a rotary engine, a cylinder, a shaft extending therethrough, a piston drum on 55 the shaft, a piston wing extending from the drum, a slideable abutment actuating the cam on the shaft, a steam chest, a rocking valve therein, a stem extending from said valve, an arm carried by said stem, an eccentric on the shaft, a pivotally mounted lever connected to said eccentric, a link block sliding in the link, a pitman connecting the block to the valve arm, a pair of auxiliary valve chambers in communication 60 with the steam chest, ports leading from said auxiliary valve chambers to the working space of the cylinder, valves in said auxiliary valve chambers, arms extending from said valves, a reversing lever, a rod extending therefrom and connected to the 65 valve arms, and a link extending from the rod and connected to the pitman.

In testimony that I claim the foregoing as my own, I have hereto affixed my signature in the presence of two witnesses.

PAUL C. BURHANS.
